ELECTRIC FURNACE

Application filed June 30, 1927, Serial No. 200,197, and in Germany June 28, 1928.

This invention relates to electric furnaces of the resistor type and has among its objects improvements in the construction and operation of such furnaces.

According to the invention, the resistor elements of furnaces of the foregoing type are so arranged and operated as to prevent, as much as possible, sudden fluctuations of the heat input into the furnace. On the contrary, the heat input in the furnace is maintained as much as possible equal to the heat requirements of the furnace during each moment of the operation thereof.

The invention will be best understood from the following descriptions of exemplifications thereof, reference being had to the accompanying drawings wherein

Fig. 1 illustrates diagrammatically the arrangement and operation of a furnace according to my invention.

Fig. 2 is a curve diagram illustrating the temperature conditions during the furnace operation and

Fig. 3 is a view similar to Fig. 1, illustrating another form of the invention.

In the operation of electric furnaces of the resistor type, such as are used for heat treatment, etc., the electrical input must be governed by the maximum allowable surface temperature of the charge, by the time required to bring up the entire body of the charge to the desired temperature, and by the soaking period during which the charge is desired to be maintained at a particular temperature. In the practical operation of furnaces, the foregoing requirements with respect to the temperature control in the furnace impose serious difficulties in the way of manufacture and operation. Thus the ob-

servance of an upper temperature limit at the surface of the charge places a restriction on the amount of energy that may be supplied to the furnace. On the other hand, economy of operation makes it necessary to carry out the process in as short a time as possible, and as a result requires the use of the largest possible amount of power for heating the furnace. As far as I am aware, heretofore the foregoing contradictory requirements have been, to a certain extent, met by supplying

the electrical energy to the furnace intermittently. In other words, the power flow into the furnace was interrupted from time to time and the magnitude of the momentary energy flow was so chosen as to secure a short heating period and bring the charge up quickly to the desired temperature. On the other hand, the number and duration of the intervals between the periods of power input were so controlled that the allowable surface temperature of the charge was not exceeded.

The foregoing prior art type of operation has serious disadvantages. The continuous connection and disconnection of the relatively large power flow places extraordinarily heavy demands on the circuit breakers, particularly in heat treatment furnaces of larger size, where the full power can only be interrupted with the aid of complicated and costly switch apparatus. If an attempt is made to reduce the number of switching operations by lengthening the heating period and the intervals therebetween, the difference between the minimum and maximum temperatures within the furnace rapidly becomes very large, meeting another limitation for this type of operation.

The periodical disconnection and reconnection of large power-consuming apparatus means also a succession of peak loads on the electrical supply line of the furnace. This has not only a highly disturbing influence on the remaining load connected to the line, such as lights, but very often reacts unfavorably on the power station itself, which, in many instances, penalizes consumers having such periodically varying power demands.

According to my invention, the contradictory requirements with respect to the furnace operation are met much better than in the foregoing prior art arrangements and systems of operation by making the power input into the furnace continuous instead of intermittent, and arranging that the electrical power supply shall be controlled in accordance with the energy streams in the furnace. Considering for the moment the energy flow conditions in the furnace at the time after the charge has reached its maxi-

55

mum surface temperature, we may distinguish two distinct energy streams. One energy stream consists of the heat flowing from the furnace to the exterior, that is, the heat loss of the furnace, by radiation, conduction and convection. This loss stream of energy is approximately constant after a steady state has been reached, because the temperature within the furnace at the exterior of the charge is constant and there is thus a constant temperature gradient between the interior and the exterior of the furnace chamber.

The other stream of energy is represented by the heat flowing from the exterior surface of the charge into the interior thereof. This charge stream varies in magnitude and depends on the momentary temperature conditions of the charge. It is largest at the beginning and decreases in the course of the heating process.

The energy that is to be supplied to the furnace is thus composed of two items, one that is constant and corresponds to the loss energy, and one that is variable and corresponds to the energy flowing into the charge. According to the invention, furnaces of the foregoing type are so arranged and operated that the electrical energy is supplied to the furnace substantially continuously, and so controlled that after the maximum permissible surface temperature of the charge has been attained, the power input at every instant is maintained equal or approximately equal to the sum of the furnace losses and the amount of energy which flows into the interior of the charge when the surface temperature is at the maximum permissible value. To this end provisions are made for controlling the power supply in accordance with the temperature conditions, both outside and inside the charge. In the preferred arrangement this is secured without interrupting the current flow into the furnace. It is also aimed to continuously utilize all the heating elements of the furnace so that the disconnection of individual elements is avoided.

Where the resistor furnace is supplied from a three-phase system coarse and fine adjustment of the heat flow into the furnace may be readily obtained as follows: for coarse adjustment the heating elements are connected either in delta or in star; fine adjustment is obtained by means of an induction regulator or regulating transformer connected into the neutral point of the star-arranged resistors.

A system of the foregoing character is shown by way of example in Fig. 1. An electrical resistor furnace 10, indicated diagrammatically by a broken line rectangle, comprises two heater groups A, B consisting each of three resistors A1, A2, A3 and B1, B2, B3 respectively. Disposed within the furnace is

a charge 11 that is to be treated. A pair of pyrometer elements u and v , in the form of thermo-couples are arranged to respond to the temperature at the surface of the charge and in the interior thereof, respectively. The resistors A1, etc., B1, etc., are arranged to be supplied from three-phase bus-bars 12 that may be connected through a main circuit breaker 13 to a polyphase supply line 14. The circuit breaker is arranged to be actuated by operating coil 15. The resistors of the heating group A are arranged to be controlled by means of a three-pole double-throw switch 21 and may be connected either in delta across the bus-bars 12 by throwing the switch 21 to the top, or in star by throwing the switch down. The switch 21 is operated from an actuating coil 22. The resistors of the heater group B may be similarly connected in star or in delta across the bus-bars 12 by means of a three-pole double-throw switch 23 that is arranged to be operated by actuating coil 24. Included in the star connection of the first mentioned heater group A is a three-phase induction regulator 25 having primary windings 26 connected across the bus-bars and secondary windings 27 connected to the lower terminals of the three-pole switch 21. A three-pole switch 28 included in the connection between the resistor elements of the second group B and the bus-bars serves to de-energize or energize said group. The switch 28 is arranged to be closed or opened by means of a pair of actuating coils 29 and 29'.

The switches 21, 23 and 28 are controlled by the above mentioned thermo-couples u and v in order to secure within the furnace and the charge the desired temperature conditions. To this end each of the thermo-couples u , v , operates a regulating device U, V, respectively, which in turn controls the operation of the several switches through relays 31, 32, 33. The regulating device U has a movable contact arm U1 moved in accordance with the effect of the temperature on the outer thermo-couple u and three contact members $u2$, $u3$, $u4$, for energizing relays 31, 32, and the cut-out coil 29' of the disconnecting switch 28 of the second resistor group B, respectively, the energy for said relays and coil being supplied from the secondary winding of an auxiliary transformer 35. Similarly, the regulating device V has a movable contact arm V1 actuated in accordance with the temperature of the internal thermo-couple v and three contact members $v2$, $v3$, $v4$, for energizing the closing coil 29 of the disconnecting switch 28, the cut-out coil 29' of said switch and the relay 33, respectively. The latter relay, when closed, establishes a circuit for energizing the cut-out coil 15 of the main switch 13, thereby disconnecting the supply from the furnace.

The resistors of the heater group A are so

dimensioned and arranged that the energy input thereof, when connected in star, is, approximately, just sufficient to cover the energy losses of the furnace. Accordingly, when only this group of resistors is connected to the supply with the elements arranged in star, the temperature of the charge will, ordinarily, never exceed the permissible value.

Referring to Figure 2 showing the curves T_a and T_i the variations of the temperature at the surface and the interior of the charge with relation to the time of heating, the operation of the furnace will be as follows:

Let us assume that the temperature indicated by the horizontal line T_m represents the maximum temperature of the charge that is desired to be reached. At the commencement of the heating process the two resistor groups A_1, A_2, A_3 , and B_1, B_2, B_3 are connected in delta to the bus-bar 12, switches 13 and 28 being closed and switches 21 and 23 being thrown to the top. Consequently, a relatively large amount of power will flow into the furnace. The charge will be heated up quickly and the temperature-time curve for the surface of the charge will show a rapid rise as indicated by the first part of curve T_a in Figure 2. The internal temperature of the charge will rise more slowly, however, corresponding approximately to the curve T_i . Shortly before the surface temperature of the charge T_a reaches the maximum value T_m , at a time point t_1 , the regulating device U will come into operation and the contact arm U_1 will reach the position opposite the contact member v_2 . This energizes the relay 31, which closes the operating circuit for actuating coil 22, thereby throwing the delta-star switch 21 to the downward position, re-connecting the resistors A_1, A_2, A_3 from delta to star. The power input is thus reduced as indicated by the first step in the power input curve W of Figure 2.

After a time t_2 when the maximum temperature T_m has been reached, the contact arm U_1 of the regulating device moves to contact member v_3 , operating relay 32 to cause energization of the actuating coil 24 of the second delta-star switch 23. As a result the switch is thrown down re-connecting the elements of the second heater group B from delta to star, thus further reducing the power input.

If, as a consequence of the gradual heating-up of the interior of the charge, the temperature still tends to exceed the prescribed limit, the contact arm U_1 moves to the contact member v_4 , energizing the cut-out coil 28 of the disconnecting switch 28, thus disconnecting the second resistor group B from the line. The remaining resistor group A continues to operate in star connection.

As pointed out above, the dimensions of the resistor group A are such that when connected in star they will just about supply the

furnace losses and, accordingly, the furnace will continue to operate in this condition. However, if further regulation is required, this is effected by the second or high temperature regulating device V as follows:

This regulating device V is controlled by the internal thermo-couple v entirely independently of the other regulating device. Until a surface temperature just below the temperature limit T_m is reached, the contact arm V_1 remains on the contact member v_2 , assuming that temperature conditions affecting pyrometer u are such that contact arm v_1 has not moved to contact v_4 , thereby causing the resistance group B to remain connected to the line. If the internal temperature of the charge begins to approach the maximum value T_m , corresponding approximately to a time point t_3 , the contact arm V_1 moves to the contact member v_3 , thereby opening the disconnecting switch 28 and cutting off the second group B from the supply source. If the internal temperature still continues to rise, however, and the maximum is exceeded, the contact arm V_1 finally moves into contact with the contact member v_4 . This operates the relay 33 and there-through effects the disconnection of the bus-bars by means of switch 13, thereby cutting off the entire supply to the furnace. This may, for instance, take place at a time point t_4 indicated in Figure 2.

The power input curve W shows thus how the power supplied to the furnace is gradually reduced in small steps. Under normal condition it is intended that after a time t_3 the resistor group A shall remain connected to the line, the power input of this group being just sufficient to cover the furnace losses during the soaking period of the charge. It is only under abnormal or extreme conditions that entire disconnection of the furnace is contemplated.

As pointed out above, the provision of the induction regulator 25 is intended to serve for the gradual variation of the load in accordance with the temperature conditions of the charge. In other words, instead of having a power input curve W in the form of a series of steps, a more or less continuously-varying power input curve will be obtained by using such induction regulator. As an example of an application of this regulator I have shown a regulating arrangement comprising a driving motor 41 for the regulator for rotating the same in one or the other direction depending on the desired regulation; a regulating device 42 for controlling the operation of the motor 41; switching means 43 for connecting the regulating device 42 to the leads from the internal thermo-couple v ; and an amplifier 44 disposed in the connection between the regulating device 42 and the thermo-couple in order to secure the desired regulating effect with the amount of

regulating energy that may be derived from a thermo-couple.

The amplifier 44 may be of any familiar type, for instance, a three-electrode tube 5 having the input terminals connected with the thermo-couples and the output terminals connected to the regulator 42. The switch 43 for connecting the induction motor regulating device 42 to the thermo-couple v is 10 operated by an actuating coil 45 which is energized by the relay 31 when the resistor group A is connected in star, an additional switch 46 being included in the energizing circuit of said coil 45 in order to permit the 15 action of the induction regulator to be cut off at will.

With the foregoing arrangement the induction regulator is directly under control of the internal temperature of the charge from 20 the moment the resistor group A is connected in star. As long as the internal temperature is below the desired value, the induction regulator will boost the voltage, gradually reducing the voltage as the temperature of 25 the interior approximates the external temperature. With this arrangement fine adjustment of the power supply to conform to the particular requirements may be secured. If the temperature tends to rise above the 30 permissible value, the induction regulator will automatically reduce the voltage to prevent such rise.

In the above described example, the various switches, relays, etc., have been indicated 35 diagrammatically, as the precise structures of the relays and switches, do not constitute the subject matter of the present invention and any type of switches or relays that will operate in the way described above may be 40 used in a way familiar to those skilled in the art. The gradual variation of the power supply in accordance with the operation of each thermo-couple, by controlling a suitably connected induction regulator, may also 45 be embodied in an arrangement wherein the induction regulator is under control both of the internal as well as of the external thermo-couple. Many other arrangements of apparatus may also be employed to carry out, with 50 more or less modifications of the above described arrangements, a method of operation involving the fine and coarse regulation of the power supply to a resistor furnace in accordance with the temperature conditions 55 thereof, under elimination of complete interruption of the power supply as practiced heretofore.

The above described system of furnace regulation lends itself also for partial application, that is, for combination with systems of the type used heretofore, that is, combination of continuous and automatic power regulation with intermittent power supply. Thus, during one part of the heating process energy may be supplied con-

tinuously with gradual or step-by-step decrease of the power input until the internal temperature has reached the limiting value. Thereafter the power supply is controlled by intermittently cutting off the power to maintain the desired temperature. With such arrangement the energy conveyed to the furnace during the first portion of the process must be maintained equal to the sum of the loss of energy and of the energy corresponding to the heat flowing into the interior of the charge. The regulation of the furnace supply by control of an induction regulator presents in itself very considerable advantages and may be utilized irrespective of the application of the other features of the invention described above.

A somewhat modified form of the invention is shown in Figure 3 of the drawing. The furnace is arranged similar to Figure 1. The two three-phase resistor groups A and B of the furnace are controlled by four three-pole double-throw switches K, L, M, N, having switching members K₁, K₂, K₃, L₁, L₂, L₃, M₁, M₂, M₃, N₁, N₂, N₃, and correspondingly marked contact members K_{1'}, K_{2'}, etc., respectively. Switch K may be thrown upwardly by energizing the actuating coil k' or downwardly by energizing the actuating coil k'' . The switches L, M, N may be similarly controlled by energizing the actuating coils $l', l'', m', m'', n', n''$.

By throwing the switches K and L downward and switches M and N upward, both resistor groups A and B are connected in delta. By leaving the switches K and L unchanged but throwing the switches M and N downward, the two groups are connected in star, the second group B having an induction regulator I connected in the star point. In the next control position the switches K and L are thrown upward thereby connecting the corresponding resistor elements of groups A and B in series. The serially-connected resistor elements may be operated either in delta when the switch N is thrown upward, or in star with the induction regulator in the star point when said switch N is thrown downward. The induction regulator may be used to boost the voltage or to buck the voltage and is operated by a motor 51 which is controlled from a suitable regulator 52 in accordance with the condition of the thermo-couples u or v . An amplifier 53 is connected in front of the regulator 52. Switches 54 and 55 control the connection of the regulator to either the thermo-couple u or v . The regulator 52 may be of any well known type used for operating induction regulators to maintain a particular regulating condition, for instance, such as are described in the publication of the Brown Boveri Company, Baden, Switzerland, entitled "Revue B B C", of November, 1917, pages 240 to 242.

The operation of the several switches is

controlled by means of a low temperature regulator U and a high temperature regulator V which are actuated from two thermo-couples *u* and *v* disposed on the exterior and the interior of the charge, as explained above.

5 The low temperature regulator U has a movable contact arm U1 and contact members *u*2, *u*3, *u*4, *u*4', *u*5, *u*5', *u*6 and *u*7. When the contact arm is opposite *u*2, actuating coils *k*'' and *l*'' are energized throwing the switches K and L downwardly for energizing the heater groups A, B, in parallel. In the next position of the contact arm U1 opposite the contact member *u*3, a circuit is established 15 for energizing the actuating coils *m*', *n*', thereby causing the two heater groups A, B to be supplied in delta. In the following position of the contact arm U1 contact is established with the contact members *u*4 and *u*4', thereby energizing the actuating coils *m*'', *n*'', *k*'' and *l*''. The energization of the actuating coils *m*'', *n*'' throws the switches M and N downwardly connecting the heater groups A and B in star, the induction regulator I being included in the star connection 20 of the heater group B.

The energization of the actuating coils *k*'' and *l*'' through contact *u*4' when contact arm *u*1 moves from contact *u*3 to contact *u*4 is without further effect because the switches K and L are already in downward position; it serves, however, to insure that said switches K and L are in said position, if for some reason a sudden drop of the temperature in 25 the furnace should occur when the regulator is in some of the further positions, causing the contact arm U1 to move backwardly to contact *u*4. The energization of said actuating coils *k*'' and *l*'' through contact *u*4' which is connected to contact *u*2, would cause said switches K and L to again re-establish the parallel operating connection for the heater groups A and B.

In the next following position of the contact arm U1 opposite the contact members *u*5, *u*5', the actuating coils *k*', *l*', and *m*', *n*' are energized. This throws the switches K, L, M, N, upwardly thereby establishing series connection between the elements of 30 the heater groups A and B and connecting said elements in delta to the supply. The heater elements A and B are so proportioned and dimensioned that, in general, the heat input in the furnace with said elements connected in series-delta will be insufficient to raise the temperature in the furnace chamber or on the surface of the charge above the maximum permissible value as long as there is a heat flow into the interior of the charge 35 in addition to the energy loss to the outside of the furnace.

As a measure of safety the regulator is provided with an additional contact member *u*6 which causes energization of the cut-out coil 16 of the main circuit breaker 13, thereby

cutting off the entire supply from the furnace in case the furnace temperature on the exterior of the charge exceeds a maximum safe limit. The regulator *u*6 is also provided with a segmental contact member *u*7 opposite the contacts *u*4 for causing the switch 54 to pick up, thereby establishing a circuit connecting the regulator 52 to the external thermo-couple *u* so as to gradually decrease, or in general, vary the voltage applied to the star-connected heater group B in accordance with the temperature rise or condition in the furnace.

The high temperature regulator V is controlled by the internal thermo-couple *v* and has a movable contact arm V1 cooperating with the plurality of contact members *v*2, *v*3, etc. When the contact arm V1 is opposite the contact *v*2, the actuating coils *m*', *n*' are energized throwing the switches M and N toward the top, thereby connecting the heater groups A and B in delta. In the next position of the contact arm opposite the contact member *v*3, the actuating coils *m*'', *n*'' are energized throwing the switches M and N downwardly, connecting the heater groups A and B in star to the induction regulator I. The temperature in the interior of the charge lags considerably behind the temperature of the exterior thereof. Accordingly, the regulator V is so arranged that the contact arm does not reach the position opposite the contact member *v*2 until approximately at the time when the contact arm U1 of the low temperature regulator U is approximately opposite the contact member *u*5.

The regulator V is also provided with a contact segment *v*4 approximately opposite the range corresponding to the contact member *v*3. This contact *v*4 controls the operation of the regulator actuating switch 55. When the contact arm V1 is opposite the contact member *v*4 the switch 55 picks up, establishing a connection between the regulator 52 and the internal thermo-couple *v* to permit regulation thereof in accordance with the rise, or in general, variation of the temperature in the interior of the charge. It is thus possible, through the action of the thermo-couple *v*, to cause the induction regulator to gradually vary the voltage applied to the series star-connected heater elements A, B in accordance with the rising temperature in the interior of the charge so as to maintain the heat flow into the furnace substantially equal to the heat demanded by the charge and the losses of the furnace.

The arrangement is such that in general the voltage controlled by the induction regulator I will be sufficient to prevent the fur-

nace temperature from rising above the maximum permissible value. However, as a safety measure, an additional contact member v_5 is provided on the regulator V for causing the circuit-breaker 13 to open if the temperature of the furnace, in particular at the point where the interior thermo-couple v is located, exceeds the maximum permissible value.

10. A system arranged as shown in Figure 3 will operate in a way similar to the system shown in Figure 1. As long as the furnace temperature is low, the regulator U will cause the two heater groups A and B to be 15 operated in parallel delta by causing the switches K, L to be in downward position and the switches M, N in upward position. The rising temperature will cause the regulator U to change the connection of the two 20 parallel heater groups A and B from delta to star, with supplemental control of the energy input through the induction regulator I during the period when the heater groups are connected in star. Further rise of the 25 furnace temperature will thereupon cause the regulator U to re-connect the two heater groups A and B in series with the elements supplied in delta by bringing the switches K, L, M, N to the upward position. With 30 the further rise of the temperature the regulator V , which is actuated in accordance with the interior temperature of the charge, comes in operation and causes the series-connected heater groups A and B to be re-connected in 35 star with gradual variation of the heat input through the action of the induction regulator I.

Many other modifications of the invention and amplifications thereof will suggest themselves to those skilled in the art. It is, accordingly, desired that the appended claims be given a broad construction commensurate with the scope of the invention.

I claim:

40. 1. The method of operating a resistor furnace which comprises first controlling the power input into the furnace in accordance with the surface temperature of the charge during the initial period of the heating of the charge, second subsequently controlling the power input in accordance with the internal temperature of the charge, said first controlling action operating independently of the second until a given maximum temperature is about to be reached, said second 45 controlling action operating independently of the first after said maximum temperature is about to be reached and until such maximum is substantially exceeded.

50. 2. In a resistor furnace for heating a charge, two heater elements, a source of supply, means for maintaining continuous power supply to said furnace until the surface temperature thereof has reached a pre- 55 determined permissible value, and means

whereby further supply of power to the furnace is continuously controlled to maintain the same substantially equal to the momentary loss of energy to the exterior of the furnace and the heat flow into the charge, said first means operating independently of the second until said predetermined value is about to be reached, said second means operating independently of the first until said value is substantially exceeded.

3. In a resistor furnace for heating a charge, a plurality of heater elements, a supply line therefor, and means for controlling the supply to said elements responsive to the temperature at the exterior of the charge 75 and in the interior thereof for controlling the power input in the said furnace, the means responsive to the charge exterior temperature operating independently until a given maximum temperature is about to be 80 reached, the means responsive to the charge interior temperature operating independently after said maximum temperature is about to be reached and until said temperature is substantially exceeded.

4. In a heater device of the class described, a plurality of heater elements, a supply line, control means for establishing a plurality of coarse control connections for varying the power supplied to said heater elements in 90 coarse steps, control means for securing fine control of the power input into said furnace, a pair of independent pyrometer elements for regulating the power supply in accordance with the temperature conditions in the furnace, one of said pyrometers controlling said power supply during one temperature range, the other of said elements controlling said power supply during another temperature range, and means for causing said fine 95 control means to be actuated in accordance with the condition of one or the other of said pyrometers.

5. In a heater furnace of the class described for heating a charge, a plurality of heater elements, a source of supply, control means for establishing high and low energy input connections between said heater elements and said supply line, means for gradually varying the voltage applied to said 100 elements from said source, a pair of pyrometers, one of said pyrometers being directly responsive to the surface temperature of said charge and causing regulation of said control means within low temperature range, the other of said pyrometers being directly responsive to the interior temperature of 105 said charge and causing regulation of said control means in the high temperature range, and means for causing said voltage control 110 means to be operated from one or the other of said pyrometers during their respective independent periods of control of the operation of said control means.

6. The method of operating a polyphase 115

electric furnace having two resistor elements and means for connecting said resistor elements in delta or star connection with a source of current which comprises supplying said resistor elements in delta for rapidly heating the furnace, re-connecting one of said elements in star independently of the other element, subsequently reconnecting said other of the elements in star independently of the first one of said elements so connected, and gradually varying the temperature of the furnace while connected in star through the control of the voltage applied to one of the star connected resistor elements.

In testimony whereof I have hereunto subscribed my name, at Zurich, Switzerland, this 27 day of May, A. D. 1927.

GÖTTLIEB KELLER.
